ATTORNEY

UNITED STATES PATENT OFFICE.

WILLIAM H. DOUGLAS, OF KEYPORT, NEW JERSEY.

LATCH FOR AUTOMOBILE DOORS.

Application filed March 14, 1923. Serial No. 624,894.

To all whom it may concern:

Be it known that I, WILLIAM H. DOUGLAS, a citizen of the United States, and resident of Keyport, in the county of Monmouth and State of New Jersey, have invented certain new and useful Improvements in Latches for Automobile Doors, of which the following is a specification.

The invention relates in general to a latch for securing doors, windows and other closures and specifically relates to a latch for use in connection with doors which are subject to vibration, such as the doors of an automotive vehicle. In the present form of latch and lock constructions the major part is mounted on the door and when the door is of frail construction, such as in certain forms of automobile doors, the lock mountings have a tendency to weaken the door as it is usual to mortise or recess the parts into the door construction and it not infrequently happens that this must be done at a point where the door is otherwise weakened by the positioning of windows and other structural parts. On the contrary, the door pillar or other frame part against which the door abuts, is of more substantial construction than the door and it is thus better capable of providing ample support of the latch parts than is the case with the door.

Accordingly, one of the primary objects of this invention is to provide a simple form of latch construction in which the separable parts are apportioned so that practically all of the latch mechanism is carried by the body pillar, leaving on the door substantially nothing more than is necessary to provide the usual handle on opposite sides of the door together with the usual handle. Difficulty has been experienced in the manufacture of high grade automobile bodies to insure a tight, snug fit of the door against the door pillar so as to eliminate rattle. The parts heretofore have had to be constructed either with such looseness of fit that the parts would catch when the door was carelessly slammed into closer position, or else, there had to be such a close interfitting of the parts that care had to be exercised in order to insure the catching of the latch parts after the door was slowly and firmly seated in its closed position.

Another object of the invention is to pro-

vide a simplified form of latch construction of the class outlined, the operative parts of which can be moved promptly into an inoperative position so as to permit the opening of the door by the simple turning of the handle on either side of the door.

Another object of the invention, is to provide a cushion between the latch parts and the containing casing for the purpose of permitting a slight shifting or freedom of relative movement between the door and the frame and in this way avoid any rigidity of construction between the door and its frame.

Another object of the invention is to provide a latch construction which will feature economy in construction, simplicity of parts and ready accessibility to housed parts for the purpose of repair or substitution of worn elements.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawing:

Figure 1 is a perspective view of the door construction of an automobile showing a preferred embodiment of the invention positioned thereon.

Figure 2 is a plan view of the keeper shown on the door frame in Figure 1 and with the cover plate removed, and showing the coacting latch shaft in dotted outline.

Figure 3 is a transverse sectional view taken on the line 3—3 of Figure 2 and showing in dotted lines the latch shaft in operative engagement therewith.

Figure 4 is a view in side elevation of the latch plate shown on the door in Figure 1.

Figure 5 is a view in left end elevation of the latch plate shown in Figure 4, and

Figure 6 is a transverse sectional view taken through the latch plate and taken on the line 6—6 of Figure 4.

In the following description and in the claims, parts will be identified by specific names for convenience of expression but

they are intended to be as generic in their application to similar parts as the art will permit.

In the drawing there is shown a portion 5 of the side of an automobile which includes the side frame 10 containing the door opening 11, outlined on one side by the door pillar 12, against which abuts the door 13, secured in closed position to the pillar 12 10 by means of the latch particularly constituting the subject matter of this disclosure.

The latch comprises in effect two separable parts, a keeper 14 carried by the pillar 12 and a latch plate 15 carried by the 15 door 13.

The latch plate 15 comprises an attachment plate 16 secured by means of screws 17 to the edge 18 of the door which engages the door pillar.

20 A pair of spaced apart journals, 19 and 20, project outwardly from the plate 16, and the usual handle-shaft 21 hereinafter referred to as a latch shaft is rotatably mounted in these bearings.

25 A shaft extends transversely of the door and in the general direction of movement of the door in moving to and from its closed position. The shaft 21 is provided on its outer end with a handle 22 which 30 projects outwardly of the door and in general resembles conventional forms of such handle construction. The opposite end of the shaft extends inwardly of the door and is shown in Figure 4 to have a squared portion 23 constituting the hub of the inside handle 24 as shown in Figure 1. The portion 25 of the shaft 21 positioned between the bearings 19 and 20 is exposed outwardly 35 of the edge 18 and as shown in Figure 6 is non-circular in cross section. This non-circular construction is preferably formed 40 simply by flattened opposite sides of the shaft so as to form a pair of oppositely disposed, flat, relatively low portions 26 alternating circumferentially with relatively high rounded portions 27. A spring 28 housed within the bearing 20 acts on the shaft 21 to maintain the same normally in position with the high points 27 disposed in 45 a plane parallel to the plane of the attaching plate 16 for purposes hereinafter explained.

50 The bearing 20 constitutes a boss opposite sides 29 of which converge inwardly towards the inside of the car so as to form a wedging engagement with the striker plate carried by the door pillar hereinafter described.

It will be seen from this construction that the entire latch plate except for holding screws is positioned exteriorly of the door or at least flush with the door edge and this construction tends to strengthen the door rather than weaken it as was true of the prior inset constructions. Of course it is

within the scope of this disclosure to inset the attaching plate 15 where this construction will tend to present a neater construction and thus to insure a snug setting of the door in its door frame.

On the contrary the keeper 14 is designed, particularly where the latch is used in automobile door constructions, to be inset in the door pillar or other similar part of the door frame. The keeper includes a flat base plate 70 30, on one side of which is positioned a heavy casting 31 constituting a mounting plate, and which mounting plate and associated parts are secured in position by a cover plate 32 secured in place by screws 80 33 at the top and bottom of the keeper which act additionally to secure the keeper as a whole to the door pillar. The cover plate is provided with an opening 34, and similarly the mounting plate is provided with 85 an opening 35, both of which extend transversely across the face of the keeper as shown more particularly in Figure 2.

The openings are designed coaxially to accommodate the bearings 19 and 20 together with the non-circular portion 25 of the latch shaft and for this purpose one side of the openings 34-25 is frusto pyramidal as shown as 36 to accommodate the similarly shaped bearing or boss 20 and the 95 opposite end of the openings 34-25 is enlarged as shown at 37 to accommodate the bearing 19.

90 It is understood from this construction that when the door is closed the parts projecting from the plate 16 are contained within the outlines of the keeper casing and the cover plate 32 contacts with the front of the plate 15 or the adjacent part of the edge 18 of the door.

100 The mounting plate is drilled on opposite sides of the opening 35 to provide pivot holes 38 in which are mounted pivot pins 39 extending laterally from each of a pair of clutch dogs, 40, the free ends, 41, of 110 which extend into the opening 35, and into the path of the non-circular portion of the latch shaft. When in operative position, the dogs extend towards each other and their ends are off-set slightly towards the inside 115 of the car from the line *a-b* connected their centers of rotation. Each of the clutch dogs is maintained in its clutching position by means of a coil spring 42, arranged so that each dog forms a one-way 120 acting clutching detent for engaging the latch shaft when disposed in operative engagement therewith as shown in Figure 3. Preferably the ends of each of the dogs fit into shoes 44 which provide an extensive 125 surface engagement on the shaft 21.

130 For the purpose of permitting a slight, cushioned movement between the latch parts and the casing, a rubber gasket 43, in two parts as shown in Figure 2, is positioned be-

tween the mounting plate and the cover plate, thus preventing any play between these two plates and this gasket is also positioned between the mounting plate and the 5 cover plate to minimize any tendency of the cover plate to scrape against the mounting plate. On the other hand, the door is free to move in its usual weaving action while the vehicle is in motion for the mounting 10 plate is permitted a limited freedom of movement against the parts of the cushion. The action of the holding screws 33 is to bear on the cover plate, which in turn causes a slight compression of the rubber gasket. 15 Pressure on the gasket is continued until the cover plate contacts with the dogs so as to maintain the same in firm pressing engagement with the mounting plate, and in this way eliminate any tendency of the dogs 20 to rattle against either the mounting plate or the cover plate.

In operation it will be understood that the spring 28 acting on the latch shaft will maintain its non-circular portion in such 25 position that the movement of the rounded face of said portion into engagement with the dogs will act thereon to shift the dogs out of their normal position, extending into the opening as shown in Figure 2 and will cause the dogs to clutch the shaft as shown 30 in Figure 3 and as is well known one-way slip clutch connections. This clutching action will positively prevent the movement of the shaft in a direction to open the door but will permit the door to move towards its closing position and in the direction indicated by the arrow in Figure 2. The door will catch simply provided that it is approximately in closed position. It has been found that the jarring of the door incidental to the driving of the vehicle will cause the door to move aggressively to a fully closed position and with the boss 20 in wedging engagement with the part of the mounted plate outlining the opening in the keeper. In this respect the keeper constitutes in effect a striker plate. The latch shaft is held from outward movement by the clutching action of the dogs but is substantially unrestrained from any closing movement until the door is firmly seated in its closed position.

When it is desired to open the door, it is necessary simply to turn either one of the handles and move the door into open position. The turning of the handle rotates the shaft so as to remove the high points of the non-circular portion from engagement with the dogs and to bring the low points opposite the dogs. The low portions have been so proportioned that they are spaced slightly from the projected dogs, thus permitting the withdrawal of the shaft axially from its engagement with the keeper on the opening movement of the door. Releasing

tension on the shaft handle permits the spring controlling the latch shaft to rotate the shaft into its normal position and thus bring the high points into their normal operative position ready to be engaged by the 70 dogs on the next closing movement of the door.

By means of a device of this character, it is possible to mount a simplified and improved form of door latch on an automobile door construction in those cases where the door element is relatively frail and incapable of supporting mortised locks and the like. Practically all the operative parts can be neatly housed within the door frame and may therefore be made as rugged as the construction requires. Doors of this character must necessarily have a handle construction and the latch herein disclosed simply utilizes the necessary handle shaft as the attaching element required to be carried by the door. With the construction herein disclosed, it is simply necessary to slam the door towards its closed position and the latch, if it catches 80 at all, will positively and automatically move the door into a securely closed position. 85

While I have shown and described, and have pointed out in the annexed claims, certain novel features of my invention, it will 90 be understood that various omissions, substitutions and changes in the form and details of the device illustrated and in its operation may be made by those skilled in the art without departing from the scope of the 95 invention. 100

Having thus described my invention, I claim:

1. In a device of the class described, the combination of a keeper casing having an 105 opening in one side thereof, a pair of clutch dogs pivotally mounted in the casing on opposite sides of the opening and having their free ends projecting towards each other and into the opening, and a latch 110 shaft mounted for rotary movement and adapted to be moved into said opening, said shaft having oppositely disposed high portions alternating circumferentially with oppositely disposed low portions, said low 115 portions being spaced from the dogs in all positions of the same whereby the shaft may be rotated into position free of the clutching action of the dogs and said high portions adapted to engage the dogs to move 120 the same in one direction and into a one-way slip clutch connection with the shaft to prevent its movement axially in one direction while permitting its corresponding movement in the opposite direction. 125

2. In a device of the class described, the combination with a keeper comprising a base plate, a mounting plate, a clutch dog pivotally mounted to the mounting plate, a cover plate having an opening therethrough 130

and means for securing the parts of the keeper in place, of a coacting latch plate comprising a manually actuated latch shaft mounted for rotary movement and having a non-circular part adapted to be moved through the opening in the cover plate, said part in one rotative position thereof operatively engaged by the dog to prevent axial movement of the shaft in one direction and in another rotative position of the shaft, said part being clear of the dog to permit bodily movement of the shaft into and from the keeper.

3. In a device of the class described, the combination of a latch plate provided with two-spaced apart bearings, a latch shaft journalled in said bearings, a handle at one end of the shaft, a portion of the shaft being exposed between the bearings, said exposed portion being non-circular in cross section and clutch means for engaging said non-circular part of the latch shaft.

4. In a device of the class described, the combination of a latch plate including an attaching plate, a bearing projecting from one side of the attaching plate, said bearing having a wedge forming part, a latch shaft journalled in the wedge forming bearing and means for engaging the shaft and adapted to coact therewith to cause the wedge forming bearing to move into a wedging position.

5. In an automobile door construction the combination with a door pillar and a door, of a latch for securing the door to the pillar, said latch including a single control shaft extending transversely of the door, provided at one end with a handle and journalled on the edge of the door adjacent the pillar, and all other parts of the latch carried by the pillar and substantially contained within the outlines of the pillar whereby practically all of the latch is supported by the pillar and only the control shaft with its handle carried by the door.

6. In a door construction, the combination with a door pillar and a door, of a latch for securing the door to the pillar, said latch including a single shaft mounted at an edge of the door adjacent the pillar and relatively movable clutch elements carried by the pillar within the edge adjacent the door operatively controlled by the shaft and adapted to clutch the shaft automatically when the latter is moved into operative relation thereto on closing the door.

7. In an automobile door construction, the combination with a door pillar and a door having an abutting engagement therewith, of a latch for securing the door in closed position engaging the pillar, said latch including separable parts comprising a control shaft together with its mounting, and clutch elements for engaging the shaft, said latch parts being apportioned with its

greater part carried by the door pillar and its lesser part, comprising the control shaft and its mounting, carried by the door whereby the door is required to carry a minimum proportion of the latch parts.

8. In a door construction, the combination of a door pillar and a door abutting the same of a latch for securing the door in closed position engaging the pillar, said latch including parts carried by the adjacent edges of the pillar and door, substantially all of said latch being positioned exteriorly of the door and contained within the adjacent edge of the pillar when the door is in closed position and said latch including a control shaft carried by the door and clutching elements carried by the door pillar for engaging the shaft.

9. In a door latch for automobiles the combination of a keeper adapted to be mounted on the door pillar, a clutch shaft adapted to be mounted on the automobile door and extending axially in a general direction of the closing movement of the door, said keeper provided with a one-way acting clutch dog adapted to engage the shaft and to act thereon to prevent any opening movement of the door while permitting any possible movement of the door in its closing direction whereby the jarring incidental to the running of the automobile will tend to effect automatically a movement of the door into its fully closed position.

10. In a door latch for automobiles, the combination of a keeper adapted to be mounted on the door pillar, a latch plate adapted to be mounted on the door, a one-way acting slip clutch having one member mounted on the keeper and a coacting member mounted on the latch plate, said clutch acting to prevent any opening movement of the door while permitting a creeping of the door from a loose closing position into a more positive closing position automatically by the jarring action of the automobile.

11. In a door latch, the combination of a keeper constituting a striker plate and provided with an opening for receiving a latch shaft, a movable detent carried by the keeper, a spring acting on the detent and tending to project the same into the opening and into the path of movement of the latch shaft, a latch plate having a latch shaft mounted thereon, said shaft having a portion thereof designed to enter the opening to engage and move the detent in a direction to shift it against the tension of the spring and into position to cause it to operatively engage said shaft portion to secure the keeper to the latch plate.

12. In an automobile door construction, the combination with a door pillar and a door, of a latch connection for insuring the closing of the door automatically by the

jarring of the same from a loose into a more positive closing position, said connection including a one-way slip clutch disposed normally to prevent opening movement of the door and to permit any creeping of the door in its closing direction.

13. In a door latch for automobiles, the combination of a keeper constituting a striker plate and provided with a wedge-shaped opening, a latch plate having a wedge-shaped boss fitted to the opening when the door is fully closed and a one-way acting clutch connection between the keeper and latch plate functioning normally to prevent an opening movement of the door and permitting a closing movement of the door with a resulting wedging of the boss into the opening.

14. In an automobile door construction, the combination of a keeper constituting a striker plate carried by the door pillar, a latch plate carried by the door, a one-way clutching connection between the keeper and latch plate normally preventing an opening movement of the door while permitting a closing movement of the door, and said connection operatively responsive to the jarring of the automobile to effect automatically a movement of the door from a partially closed position into a more fully closed position.

15. In a door latch for automobiles, the combination of a keeper adapted to be mounted on the door pillar, a latch plate adapted to be mounted on the door, a one-way acting slip clutch having one member mounted on the keeper and a coacting member mounted on the latch plate, said clutch acting to prevent any opening movement of the door while permitting a creeping of the door from a loose closing position into a more positive closing position automatically by the jarring action of the automobile, and manually actuated means for moving the clutch members relative to each other into an inoperative position to permit an opening movement of the door.

16. In a door latch for automobiles, the combination of a keeper constituting a striker plate and provided with a wedge-shaped opening, a latch plate having a wedge-shaped boss fitted to the opening when the door is fully closed, and a one-way acting clutch connection between the keeper and latch plate functioning normally to prevent an opening movement of the door and permitting a closing movement of the door with a resulting wedging of the boss into the opening and means for moving the clutch into an inoperative position to permit an opening movement of the door.

17. In a door latch, the combination of a keeper constituting a striker plate and provided with an opening for receiving a latch shaft, a movable detent carried by the

keeper, a spring acting on the detent and tending to project the same into the opening and into the path of movement of the latch shaft, a latch plate having a latch shaft mounted thereon, said shaft having a portion thereof designed to enter the opening to engage and move the detent in a direction to shift it against the tension of the spring and into position to cause it to operatively engage said shaft portion to secure the keeper to the latch plate, and means for rotating the latch shaft out of its operative engagement with the detent thereby to permit the separation of the keeper and latch plate.

18. In an automobile door construction the combination with a door pillar and a door, of a latch connection for insuring the closing of the door automatically by the jarring of the same from a loose into a more positive closing position, said connection including a one-way slip clutch disposed normally to prevent opening movement of the door and to permit any creeping of the door in its closing direction, and a manually actuated control for moving the clutch into an inoperative position thereby to permit an opening movement of the door.

19. In a door construction, the combination of a door pillar and a door, of a latch including a keeper secured to the door pillar and having an opening exposed on the side adjacent the door, a latch plate secured to the abutting edge of the door, a latch shaft journaled in said plate extending axially in the general direction of the opening movement of the door and adapted to be moved into said opening when the door is closed and a clutching member adapted to engage the contained portion of the shaft to secure the door in closed position.

20. In a device of the class described, the combination of a keeper casing having a shaft opening in one side thereof, a clutch dog pivotally mounted in said casing and having its free end projecting into said opening, a latch shaft mounted for rotary movement and adapted to be moved into said opening, said shaft when in one of its rotative positions acting on the dog to displace the same from its normal inoperative position and to move the free end of the same into a position clutching the shaft.

21. In a door latch, the combination of a keeper provided with a clutch dog, a latch plate provided with a latch shaft mounted for rotary movement, adapted in one position thereof to be moved into engagement with the dog to shift the same from its normal inoperative position and into clutching engagement with the shaft.

22. In a door latch, the combination of a keeper provided with a clutch dog, a latch plate provided with a latch shaft mounted for rotary movement, adapted in one posi-

- tion thereof to be moved into engagement with the dog to shift the same from its normal inoperative position and into clutching engagement with the shaft, and a spring 5 acting on the shaft to maintain the same in its normal dog shifting position.
23. In a door latch, the combination of a keeper provided with a clutch dog having a normal inoperative position and a shifted 10 operative position, a shaft having a portion non-circular in cross-section adapted to be moved into position clutched by the dog, said shaft rotatable into position to bring a low point of the non-circular portion opposite the dog and thus permit the shaft to escape from the dog.
24. In a door latch, the combination of a keeper provided with a one-way acting clutch dog, a shaft free to move axially in 15 one direction and in one rotative position thereof operatively engaged by the dog and restrained thereby from movement in the opposite direction, said shaft provided with a depressed portion which, when the shaft 20 is rotated to bring the same opposite the dog, clears the shaft from the clutching engagement of the dog and thus permits the shaft to be moved in said opposite direction.
25. In a device of the class described, the 25 combination of a keeper casing having a shaft opening in one side thereof, a clutch dog pivotally mounted in said casing and having its free end projecting into said opening, a latch shaft mounted for rotary movement and adapted to be moved into said opening, said shaft when in one of its rotative positions acting on the dog to displace the same from its normal inoperative position and to move the free end of the same into a position clutching the shaft and said shaft provided with a handle for rotating the shaft out of operative relation, to the clutch dog and thus permit the separation of the latch shaft from the keeper casing.
26. In a door construction, the combination of a door pillar and a door, of a latch 30 including a keeper secured to the door pillar and having an opening exposed on the side adjacent the door, a latch plate secured to the abutting edge of the door, a latch shaft journalled in said plate extending axially in the general direction of the opening movement of the door and adapted to be moved into said opening when the door is closed and a clutching member housed 35 within the casing adapted to engage the contained portion of the shaft to secure the door in closed position, and a handle on one end of the shaft for rotating the same out of operative engagement with the clutching 40 member and thus permit the door to be opened.
27. In a device of the class described, the combination of a base plate, a mounting plate on one side thereof, clutch elements 45 carried by the mounting plate, a cover plate for securing the clutch elements and mounting plate to the base plate and a resilient packing between the cover plate and base plate.
28. In a device of the class described, the combination of a base plate, a mounting plate on one side thereof, clutch elements carried by the mounting plate, a cover plate for securing the clutch elements and mounting plate to the base plate and a cushioning member disposed between the mounting plate and cover plate and between the cover plate and the base plate.
29. In a latch for an automobile door 50 construction, the combination of a mechanism containing casing, clutch mechanism contained in said casing, and cushioning means within the casing for preventing the clutch mechanism from rattling while permitting a slight freedom of movement between the clutch mechanism and the casing.
- Signed at New York in the county of and State of New York this 1st day of March, A. D. 1923.

WILLIAM H. DOUGLAS.
